CLAIM

The ornamental design for a snack food product package, as shown and described.

DESCRIPTION

FIG. 1 is a top plan view showing my new design carrying snack products;

FIG. 2 is an end elevational view of my new design shown in FIG. 1;

FIG. 3 is a side elevational view showing my new design shown in FIGS. 1 and 2; and,

FIG. 4 is a perspective view showing my new design with food products as shown in FIGS. 1, 2 and 3.

The oposite side view of FIG. 3 is a mirror image of the view shown, and the opposite side view of FIG. 2 forms no part of the claimed design.
